ELECTRODYNAMIC LOUD SPEAKER

Erwin Gerlach and Heinz Orlich, Berlin-Siemensstadt, Germany, assignors to Siemens & Halske, Aktiengesellschaft, Siemensstadt, near Berlin, Germany, a corporation of Germany

Application December 26, 1931, Serial No. 583,297,
and in Germany September 16, 1930

8 Claims. (Cl. 179—115.5)

The invention is concerned with a horn type electrodynamic loud speaker which distinguishes itself by an extremely good reproduction of the highest and the lowest pitches with satisfactory efficiency.

Horn loud speakers based upon the electrodynamic drive principle are fundamentally known in the art. These known loudspeaker constructions generally comprise a circular, calotte-shaped or conical diaphragm with a circular oscillation coil. Other known embodiments are furnished with coils of square shape, especially loud speakers with four pole magnet systems. In the systems known in the prior art, however, only about one half of the active wire length is utilized, with a resultant poor efficiency of the arrangement. The magnet system in this case is adapted to the form of a coil, just as in the known loud speakers with square coils whose magnet system consists of a square middle pole and two pole shoes which are disposed upon two opposite sides of the central pole.

In order to insure faithful reproduction and a high efficiency it is imperative to make the oscillating system as light in weight as feasible and to raise the field intensity of the air-gap to a maximum value. However, the lightness of the diaphragm should not be driven to a point where rigidity is impaired as a consequence. In fact, up to the highest frequencies, generally up to 8,000 cycles, the diaphragm should oscillate en bloc or piston fashion (as a rigid whole), and this is possible only if the diaphragm is of maximum stiffness.

In the case of diaphragms of circular, calotte and cone-shape, an increase in rigidity is insured with the sacrifice of lightness or an increase in volume or mass. But this fact, in turn, impairs the reproduction particularly of the high frequencies.

Now, the present invention is predicated upon a recognition and understanding of the fact that an improvement of electrodynamic loudspeakers is feasible by a departure from, or abandonment of, the customary circular form of the diaphragm with a circular coil. Hence, according to the invention an angular, preferably a rectangular form of diaphragm is used in combination with a square coil. To be more precise, it has been found to be most advantageous to make the diaphragm and the coil in the form of an elongated rectangle and to dispose the driving coil at the margin of the diaphragm so that a box like structure is obtained the bottom of which consists of

the diaphragm while the sides thereof are the sides of the coil.

Now the said form of construction offers a number of essential technical advantages. Known pot-type magnets are usually found in electrodynamic loud speakers with circular oscillation coil involve much leakage or dispersion so that owing to the high field intensity desirable to secure high efficiency, the utilization of the aggregated magnetic flux that is set up is greatly diminished. Another point is that the Joule heat dissipated by the energizing current of the field coil can not be readily carried away owing to the fact that the coil is built into the pot magnet with the result that the current density in the energizing coil, and thus the effective ampere turns, are able to assume only low values. However, the novel arrangement here disclosed provides improvements not only with reference to the magnet system, but also respecting the oscillating system of the loudspeaker.

In the preferably elongated and rectangular form of the diaphragm according to the invention, two natural periods arise. They are, namely, one natural period in longitudinal sense and another one in transversal direction. The former does not make itself unfavorably felt because of the cophasic drive of the diaphragm so that the diaphragm can be made any desired length. Also the load capacity may thus also be raised at will in contradistinction to what is true to diaphragms known in the earlier art where an increase in surface occasions a reduction in the natural period whereby reproduction owing to the occurrence of the resonance peak is substantially reduced.

The width of the diaphragm may be readily chosen so that the transversal vibration of the diaphragm can be shifted to a very high point, in fact, close to the limit of the frequency range or band preferably or predominantly to be reproduced. The transversal vibration may also be shifted by means of reinforcement ribs or fins and corrugations as is well known in the art. The weight of the diaphragm in this manner may be kept far lower than in the case of a circular diaphragm possessing identical acoustic properties. According to the present invention it has been feasible to develop systems in which, in the presence of a transversal natural vibration of about 6,000 cycles, i. e., a diaphragm of great rigidity the oscillating system (diaphragm and conductor) involved a weight of less than 0.08 gram per square centimeter of effective surface. The diaphragm may be considered, compared to

the transformation space, as an air tight diaphragm since a pressure transformation of a ratio of at least 1:10 is provided for the purpose of increasing the efficiency. This is the ideal oscillating diaphragm to be striven for. The marginal drive prevents the arising of partial vibrations in the diaphragm. The leverage between the driving force and the supporting means is nearly of zero value due to the fact that the driving force acts upon the diaphragm in the neighborhood of the diaphragm supporting means. As a result the diaphragm is able to respond en bloc (piston fashion) to the motions of the coil.

In addition to these acoustic advantages the new loud speaker here disclosed offers substantial advantages also in manufacturing respect. Simple straight ground magnet pieces may be used for the construction of the magnet system. The magnet system may also consist of a U-shaped piece having the preferably rectangular and elongated middle pole disposed in the middle thereof. Preferably, pole plates are placed upon the lateral limbs. If desired the plates may be connected by means of screws and slots with the lateral limbs in order to allow for an adjustment of the air gap between the pole plate and the center pole. The shape of the elongated rectangle for the center pole, inter alia, offers the advantage that the dynamically acting transverse sides of the oscillation coils corresponding in shape to the form of the middle pole, may be chosen very short in reference to the aggregate conductor length.

As previously pointed out the diaphragm is furnished with transversal fins or ribs in order that the transversal vibrations may be shifted as high as possible. If this diaphragm is fitted into the mouth of the horn or funnel, then the compression space is unnecessarily enlarged by the space between the reinforcing ribs or fins or corrugations, and the efficiency of the entire arrangement is diminished. Hence, while the diaphragm is provided with fins or corrugations forming reinforcing means, the acoustically active surface is smoothed by covering the surface of the diaphragm with tissue paper, ordinary paper, thin metal foil or some other layer of suitable substance so that the compression space is correctly pre-calculable and may be chosen and fixed at the optimum value from a technical viewpoint. The covering layer is somewhat wider than the width of the diaphragm so that strips protrude at the longitudinal edges of the diaphragm, these strips being adapted to be fixed to the outer poles. The covering surface in this manner also serves to support the diaphragm.

Owing to the cophasic drive of the entire diaphragm, and because of the fact that the distance from the end of the diaphragm to the mouth of the horn is greater than the distance between the middle of the diaphragm to the horn mouth, the pressure transformation is liable to involve a marked diminution or attenuation of certain frequency ranges or bands. This is avoided by arranging the compression space so that it is not in direct connection with or adjacent to the mouth of the funnel or horn. In fact, it is connected with the horn through channels or slots in such a fashion that the acoustic waves reaching the mouth of the horn after having been radiated off from the diaphragm, are substantially of the same phase.

The air space between the diaphragm and the central pole should be in communication laterally or through the middle pole, with the outside

air to prevent damping. According to a still further object of the invention this is insured by arranging the conductor carrying the voice or audiofrequency currents so that a little air gap is produced between the diaphragms and the coil side at the narrow ends of the diaphragm. The conductor is attached to the longitudinal sides of the diaphragm by being clamped around strips of Pertinax or the like which are connected along their edges to the diaphragm. The strips also serve as reinforcements for the diaphragm.

The invention is illustrated by the accompanying drawing in which,

Fig. 1 is an isometric view showing the magnet system and the field winding,

Fig. 2 is an isometric view showing an approved form of the assembled diaphragm,

Fig. 3 is an isometric view showing a diaphragm having a modified form of driving conductor,

Fig. 4 is a cross sectional view showing the assembled driving unit;

Fig. 5 is an enlarged view of a portion of Fig. 4, and

Fig. 6 is a side view of the assembled apparatus.

The system 1 preferably made in one piece and being of elongated form, carries the outer pole plates 2 as well as the center pole plate 3. The pole plates are adjustably secured to the poles by means of screws passing through slots in the pole plates. The interiorly disposed field coil 4 is readily able to give off dissipated heat on its transversal faces inasmuch as the same is in contact with the outside air, in contradistinction with the usual forms of construction of electrodynamic loud speakers where the magnet coil is located inside the pot. Abduction of heat is furthermore promoted by the aid of sheets or laminae 5 consisting of material possessing high heat conducting powers, which are inserted in the field coil.

Fig. 2 shows the oscillation coil 6 with the diaphragm 7 (not shown in Fig. 1). The diaphragm 7, which is provided with reinforcing corrugations (see Fig. 3), has a strip of silk 8 pasted over it. The strip of silk is somewhat wider than the diaphragm and is secured at the outer poles 2 (Fig. 2). The oscillation coil 6 which in its practically simplest form comprises just one turn or loop of wire, is pasted onto a strip of Pertinax 9 which in its turn is in rigid connection with the diaphragm 7. The comparatively large surface resulting from the corrugation assures a stiff attachment of the conductor to the diaphragm. The attachment is preferably obtained by means of pasting.

Fig. 3 shows the diaphragm and the system without the surface 8. The Pertinax strips 9, the conductor 10 pressed around the same (which corresponds to the oscillation coil in Fig. 2) as well as the reinforcement of the diaphragm consisting of corrugations 7a, can be clearly seen. The corrugations are equivalent to T-shaped reinforcements.

Fig. 4 shows, partly in section, an embodiment of the novel loud speaker which differs from the embodiment shown in Figs. 1-3, as regards the mode of securing or attaching the diaphragm. The U-magnet system 11 with the central pole 12 and the outer pole plates 13, surrounds the exciter coil 14. The coil 14 is carrying the speech or audiofrequency currents projects into the air gap between the central pole 12 and the pole plates 13. The coil 14 consisting of a single turn,

is made of a wire 15 which is pressed around the Pertinax strips 16. The strips 16 are secured to the longitudinal sides of the diaphragm 17. The diaphragm 17 is fastened to a piece of silk 5 material 18 which extends over a frame 19. The said frame 19 is secured to the plates 13.

Centering of the oscillation coil in the air gap is not attended with any difficulties. If the holes provided in the flange are placed co-axially with 10 the holes in the pole plates, the coil is able to move inside the air gap. A spacer frame 21 consisting of hard paper or sheet metal material is placed between the frame 19 which is screwed fast on the outer pole plates 13, and the flange 15 20. The pressure transformation space 22 is easily adjustable in this manner. The flange 20 is connected through the long equal length tubes 23 as shown in Fig. 6, with the attaching piece 24 which is adjacent to the mouth of the horn. 20 What we claim is:

1. A vibratile system for an electrodynamic acoustic device comprising a pair of conductors and an elongated box-like structure open at its bottom and at its two shorter ends, the top of said 25 structure constituting a sound wave producing portion, and the longer sides of said structure constituting supports for said conductors, said sides and said conductors constituting the driving portion of said vibratile system.

30 2. A vibratile system for an acoustic device of the electrodynamic type comprising an elongated rectangularly shaped sound wave producing portion, reinforcing means for said sound wave producing portion consisting of corrugations extending transversely of said sound wave producing portion, and a driving portion consisting of strips of hard paper connected along their edges substantially to the longitudinal edges of the sound wave producing portion, and a conductor pressed 40 around said strips of hard paper.

3. A vibratile system for an acoustic device of the electro-dynamic type comprising a sound wave producing portion, a driving portion, reinforcing means for said sound wave producing portion 45 comprising corrugations extending at right angles to the direction of motion of said driving portion, and a layer of silk covering the corrugations in said sound wave producing portion and extending beyond the limits of said sound wave producing portion to provide means for fastening the vibratile system to the outer pole pieces of the magnet system.

4. A magnet system for an electro-dynamic acoustic device comprising an elongated magnet 55 which is substantially E-shaped in cross section, a winding surrounding the middle limb of said

magnet arranged so that it is exposed to the outer air at the ends of said magnet, cooling fins imbedded in said winding and extending from the ends thereof into the open air, and pole plates secured to each of the limbs of said magnet and arranged to provide a pair of elongated air gaps. 80

5. A magnet for an electro-dynamic acoustic device comprising an elongated magnet system which is substantially E-shaped in cross section, a winding surrounding the middle limb of said magnet system arranged so that it is exposed to the outer air at the ends of said system, pole plates secured to each of the limbs of said magnet system and arranged to provide a pair of elongated air gaps, and laminæ of material having high heat 85 conducting properties inserted in said coil and extending outwardly therefrom into the open air whereby heat from said coil is readily dissipated. 90

6. A loud speaker of the electro-dynamic type comprising a magnet system for providing an electro-magnetic field, a diaphragm, said diaphragm consisting of a conductor portion adapted to cooperate with said magnetic field and an elongated rectangularly shaped sound wave producing portion, means providing a compression 100 space above said sound wave producing portion, and channels for connecting said compression space with an acoustic horn. 95

7. A loud speaker of the electro-dynamic type comprising a magnet system for providing an electro-magnetic field, a diaphragm, said diaphragm consisting of a conductor portion adapted to cooperate with said magnetic field and an elongated rectangularly shaped sound wave producing portion, means providing a compression 105 space above said sound wave producing portion and channels for connecting said compression space with an acoustic horn, said channels consisting of a plurality of tubes of equal length extending between a common aperture at the 110 smaller opening of said horn and different points along said elongated diaphragm. 115

8. An acoustic device of the electro-dynamic type comprising means providing a magnetic field, a diaphragm consisting of a portion for cooperating with said magnetic field and a sound wave producing portion, said sound wave producing portion having an elongated rectangular shape, a layer of silk covering said sound wave producing portion and extending there beyond, a frame 120 to which is secured the portion of said layer of silk extending beyond said sound wave producing portion, and means for fastening said frame to 125 said magnet system. 120
